L. L. SCOTT

GOLF TEE

Filed July 17, 1925

FIG. 3

FIG. 1

FIG. 2

Lewis L. Scott INVENTOR

UNITED STATES PATENT OFFICE.

LEWIS L. SCOTT, OF ST. LOUIS, MISSOURI.

GOLF TEE.

Application filed July 17, 1925. Serial No. 44,309.

To all whom it may concern:

Be it known that I, LEWIS L. SCOTT, a citizen of the United States, residing in the city of St. Louis and State of Missouri, have invented certain new and useful Improvements in Golf Tees, of which the following is a specification.

The object of my invention is to provide a gold tee that may be stuck into the ground, said tee having a definite stop so that the same exact height of tee may be obtained each time and to make this tee in a one piece construction, preferably of white birch wood, so that its cost will be very small. Another object of my invention is to so shape the tee so that it cannot be easily broken. Tees now on the market are shaped about as shown on the drawing in Figure 5 of Patent No. 1,529,517, dated March 20th, 1925. I find that the shape of tee as shown in the above referred to patent is very easily broken, due to the small diameter of the shank just under the head of the tee and also due to the distance that the shank is stuck into the ground.

I am aware that tees are now made which are adapted to be stuck into the ground to support a golf ball, but there is nothing on the market that in any way resembles my tee, nor that will accomplish what I accomplish with this tee. These tees are made in different heights so that a player can get any height of tee he is accustomed to using.

My invention is illustrated in the accompanying drawings in which:

Figure 1 is a sectional view of my one piece golf tee and it shows what I call the high tee.

Figure 2 is a sectional view of my improved golf tee and it is what I call my medium tee—it will be seen that there is a difference in the heights of tee between Figures 1 and 2. Both of these tees are shown sticking into a section of earth.

Figure 3 is a top plan view of Figure 1.

Referring now to the drawings, the numeral 1 indicates the head of this tee which is formed with a cup shape top 3, on which

a golf ball may be set. The numeral 4 indicates a shoulder on the head of this tee which forms a stop to regulate the height of said tee. The numeral 2 indicates a shank which is a part of the head, said shank being adapted to stick into the ground.

It will be noted that I have provided a golf tee to be stuck into the ground for the purpose of teeing a golf ball, which provides a definite height, and which is constructed in one piece of material that will not easily break.

I claim:

1. A golf tee formed of a single piece of material comprising a head adapted to support a golf ball and having a projecting shank directly under said head, said shank being made in two diameters, the larger diameter being adjacent to the head and the smaller diameter being adjacent to the larger diameter and having a pointed end which is adapted to be stuck into the ground.

2. A golf tee formed of a single piece of non-metallic material comprising a head adapted to support a golf ball and having a projecting shank directly under said head, said shank being made in two diameters, the larger diameter being adjacent to the head and the smaller diameter being adjacent to the larger diameter and having a pointed end which is adapted to be stuck into the ground.

3. A golf tee formed of a single piece of material comprising a head adapted to support a golf ball and having a projecting shank directly under said head, said shank being made in two diameters, the larger diameter being adjacent to the head and the smaller diameter being adjacent to the larger diameter and having a pointed end which is adapted to be stuck into the ground, said small diameter shank being relatively short in length.

In testimony whereof, I have hereunto set my hand.

LEWIS L. SCOTT.
